I. PICK.
Victorine.

No. 208,034.

Patented Sept. 17, 1878.

Fig. 1.

Fig. 2.

Fig. 3.

Witnesses.

Frederick de la Rue
68 Pall Mall
London
17 Gracechurch Street London

Inventor.

Ignac Pick

UNITED STATES PATENT OFFICE.

IGNAC PICK, OF LONDON, ENGLAND.

IMPROVEMENT IN VICTORINES.

Specification forming part of Letters Patent No. 208,034, dated September 17, 1878; application filed June 10, 1878; patented in England, September 28, 1877.

To all whom it may concern:

Be it known that I, IGNAC PICK, of the city of London, in the county of Middlesex, England, have invented a new or Improved Combined Article of Wearing Apparel for Ladies' Use, which improvement is fully set forth in the following specification and accompanying drawings.

The object of this invention is to combine a muff with the article of ladies' dress known as a "tippet" or "victorine," provided with an extension in one piece, covering more or less of the skirt, so that it may be conveniently carried on the person in such manner as to permit the hands of the wearer being readily and quickly withdrawn therefrom at any moment without fear of losing it by having to place it aside, or to hold it while the hands are required for other purposes, as is the case with the muffs now in use.

This improved combined article forms at the same time a new and elegant article of ladies' dress.

This combined article consists of a collar or tippet, bands dependent from the front of the same, an extension of the bands below the waist in one piece, and a muff located at the place where the muff is usually worn.

In one arrangement the article is adjusted or fitted on by passing it over the head, and for this purpose I cut the front thereof in two parts for a portion of its length, so as to permit a sufficient opening for the passage of the head; and when the article is on the wearer these two parts are connected together by means of hooks and eyes, buttons, or other suitable fastening contrivances.

I contemplate a modification or alternative arrangement of the bands, which consists in making that part in one piece, the tippet being divided at some other part, so as to be capable of being passed around the neck instead of over the head, as in the other case.

This combined article may depend as low in front of the dress as desired, and, in addition to forming a warm covering for the neck and a muff for the hands, it can supply the place of ornamental trimming to jackets or other outdoor costumes.

I proceed, with reference to the accompanying sheet of drawings, to describe a combined muff and tippet or victorine made according to my invention.

Figure 1 is a front elevation, Fig. 2 a back view, and Fig. 3 a side view, of the arrangement first herein described.

A is a tippet or covering for the neck and adjacent parts of the back and shoulders. A¹ A¹ are bands or extensions of the tippet A over the breast of the wearer, and made continuous therewith. A² is an extension of the bands A¹ A¹, made in one piece and continuous with those bands; and B is a muff, secured at or near the junction of the parts A¹ A¹ and A². The bands A¹ A¹ are provided with hooks and eyes or other suitable means of attachment, and are made in two parts for convenience in putting on and off.

Now, in accordance with my invention, I sew or otherwise attach to the back of the tippet or victorine A layers or pieces of silk, satin, velvet, or other suitable fabric, and the part or place where the muff is to be I stuff with eider-down, hair, wadding, or other like material, so that it forms a cushion or padding, which then constitutes the muff B. If desired, this padding may be quilted.

A second padding or cushion, B^x, similar to that forming the inside back of the muff, is placed opposite thereto, on the under side of the tippet or victorine, and forms the inside front of the muff. The space between these paddings or cushions forms a comfortable and warm receptacle for the hands of the wearer, which are introduced at the sides.

C is a pocket attached to the back of the muff, and useful for holding a purse, handkerchief, or other like article. This combined article is preferably made of furs or other suitable or warm materials, and may be padded, lined, and quilted on its upper part, so as to form a chest-protector.

I am aware that previous to my invention articles of wear have been made consisting of a tippet or collar, bands continuous therewith and pendent therefrom, and a muff attached to the ends of such bands; also, that an article of a similar kind, but having in addition two short pendants or extensions of the bands extending below the muff or pocket provided in each band, has been made prior to my invention; and I therefore disclaim the same.

Having thus described my invention, what I claim as new, and desire to secure by Letters Patent, is—

As a new article of manufacture, the victorine composed of the tippet A, bands A¹ A¹, solid extension A², and the muff B, all arranged as described and shown.

Witness my hand this 28th day of May, 1878.

IGNAC PICK.

Witnesses:

ERNEST DE PASS,
68 Fleet Street, London.
G. W. WARREN, Notary Public,
17 Gracechurch Street, London.